UNITED STATES PATENT OFFICE.

ADAM D. GOETZ, OF CHARLESTOWN, WEST VIRGINIA.

SHAFT-TUG.

No. 806,338.

Specification of Letters Patent.

Patented Dec. 5, 1905.

Application filed February 14, 1905. Serial No. 245,602.

To all whom it may concern:

Be it known that I, ADAM D. GOETZ, a citizen of the United States, residing at Charlestown, in the county of Jefferson, State of West Virginia, have invented certain new and useful Improvements in Shaft-Tugs, of which the following is a specification, reference being had therein to the accompanying drawings.

10 This invention relates to a shaft-tug, and particularly to an improvement upon the construction disclosed in my prior patent, No. 561,049, by which the use of strips joined at the heel of the buckle is obviated, and also 15 the cutting away of the central-strip to admit the tongue of the buckle is prevented, and the weakening at this point of strain consequently obviated.

20 This invention has for an object to form a tug from successive layers of material, each formed in a continuous piece and secured together with the buckle-tongue centrally disposed between contacting layers of said material.

25 Other and further objects and advantages of the invention will be hereinafter set forth and the novel features thereof defined by the appended claims.

30 In the drawings, Figure 1 is a perspective of a layer used in forming the tug; Fig. 2, a similar view of a plurality thereof; Fig. 3, a perspective showing the buckle and strap-loop applied to the assembled layers; Fig. 4, a similar view of the completed tug; Fig. 5, 35 a top plan of a modified application of the invention in which the layers are secured together in series; Fig. 6, a vertical cross-section on the line 6 6 of Fig. 5, and Fig. 7 a horizontal section through one of the sections.

40 Like letters of reference refer to like parts in the several figures of the drawings.

45 The layers A, forming the body of the tug, may be of any suitable material, preferably leather, and of any desired size and configuration. Each is formed from a single piece of material and is continuous about the central opening A' therein. These layers are secured together in alinement with each 50 other to form the desired thickness of the tug, as shown in Fig. 2, and when so assembled a suitable opening A² is formed for the introduction of the bolt B, forming the pivot for the tongue B' of the buckle, this tongue 55 being disposed between two contacting layers of the tug, as shown in Figs. 3, 5, and 6,

thus obviating the necessity of cutting any of the layers and weakening the tug at the point of greatest strain. At the opposite side of the tug a similar opening A³ is provided to receive the bolt C of the strap-loop C', which is applied at that point after the completion of the tug. The frame B² of the buckle is applied in the usual manner to embrace the outer faces of the tug and secured 60 in position by heading the bolt B as usual. In the completed article, as shown in Fig. 4, a strap-guard C² is also applied adjacent to the buckle and secured by cross-bolts C³, passing through the assembled layers of the 70 tug. In this completed form the layers are finished upon their exposed edges and afterward pressed and dried so as to stiffen and set the form of the tug.

75 The layers comprising the tug may be secured together in any desired manner—for instance, by stitching, as shown at D in Fig. 5, or riveting, as shown at D' in Fig. 6, or staples, as indicated at D² in Fig. 7; but when the assembled layers are of much thickness the plies thereof are inclined to work 80 upon each other and cut the stitches, so as to permit a separation of the parts. This is overcome by assembling the layers in a plurality of sections—for instance, as shown in Fig. 5, 85 where two of these sections are disposed one at each side of the tongue and held together by any desired means—for instance, the bolt of the buckle and other attachments to the tug. In stitching or otherwise securing together the layers forming either these sections or the complete tug it is desirable to conceal the stitches upon the face, both for producing a more finished appearance and for protecting the same from wear, and for 90 that purpose a channel or welt A⁴ may be provided upon one face, as shown in Fig. 7, and the securing means disposed therein, so that when this welt is secured in position a finished surface is presented. When two 100 sections of layers are used, as in Fig. 5, the unchanneled surfaces are placed in contact with each other and the securing means thus concealed and protected. The layers when 105 assembled about the tongue of the buckle are placed under pressure and the buckle-tongue embedded therein, so that each of the layers remains a continuous piece, thus securing the greatest strength at the point of strain and avoiding the joining at this point, which 110 greatly weakened the construction of tug.

It will also be obvious that the use of sec-

tions of the layers secured together prevents the cutting of stitches when a number of plies are superposed upon each other, while the layers used may be cut from scrap-
5 leather of various sizes and after being built to the desired thickness finished to present a uniform appearance.

It will be obvious that changes may be made in the details of construction and con-
10 figuration without departing from the spirit of the invention as defined by the appended claims.

Having described my invention and set forth its merits, what I claim, and desire to
15 secure by Letters Patent, is—

1. In a shaft-tug, a plurality of sections each separately formed of layers of material

secured together with continuous contacting faces, and a buckle-tongue disposed between the continuous contacting faces of said sec- 20 tions.

2. A shaft-tug composed of a plurality of superposed annular layers, and a buckle having its tongue pivotally mounted upon a bolt extending laterally through said layers, said 25 tongue being centrally disposed between the adjacent faces of continuous contacting layers thereof.

In testimony whereof I affix my signature in presence of two witnesses.

ADAM D. GOETZ.
